DISPLAY BOX

Lewis Douglas Young, Providence, R. I., assignor
to Douglas Young, Inc., a corporation of Rhode
Island

Application June 2, 1951, Serial No. 229,570

1 Claim. (Cl. 206—45.13)

1 This invention relates to a box or container particularly designed for displaying merchandise contained within the box.

In shipping or storing certain articles it is desirable to have a box into which the article may be placed. However, for ease of removing the article from the box or for displaying the article, it is desirable to have the support for the article inclined with reference to the surface upon which the box is placed.

One of the objects of this invention is to provide a construction of box so that when the box cover is opened or swung through substantially ninety degrees, the part upon which the merchandise or contents of the box is supported will be raised so as to be at an angle to the supporting surface upon which the bottom wall of the box rests.

Another object of the invention is to provide a raising means which will be formed from cardboard or the same material of which the box is made.

Another object of the invention is to utilize cardboard which may be provided in the box machines which are used for making the box.

More specifically, an object of the invention is to provide a tray within the body portion of the box so that when the cover of the box is lifted, the tray will be swung upwardly at an angle to the bottom wall of the body of the box and to a height above the side walls of the body of the box so as to provide a more attractive display.

Another object of the invention is to maintain the cover of the box at substantially ninety degrees to the closed position of the cover which assists in the display and takes up but a minimum amount of space when resting upon a table or some horizontal support.

With these and other objects in view, the invention consists of certain novel features of construction, as will be more fully described and particularly pointed out in the appended claim.

In the accompanying drawings:

Figure 1 is a perspective view of the box in open position;

Figure 2 is a sectional view of the box in the open position shown in Figure 1; and

Figure 3 is a sectional view with the cover of the box swung to closed position but illustrating the position of the tray within the box when in the closed position.

In proceeding with this invention, I provide a body member and a cover member and hinge these two together so that when the cover is closed, the contents of the box is concealed and protected within the box. I also provide a tray

which movably fits in the body of the box and by use of cardboard attached between the cover and the tray, I provide a construction so that when the cover is swung from its closed position through substantially ninety degrees, such as by means of a spring hinge, with the cover maintained in the ninety-degree position by the hinge, the tray will be lifted from within the body member of the box to an inclined position with reference to the bottom of the box. I accomplish this

10 swinging of the tray by providing a lining for the top wall of the cover member part way along the cover member and then extend this lining at right angles to the top wall of the cover to a point 15 into the body member of the box providing a lever of a stiff piece of cardboard and I connect this right angularly extending lever from its lower end to a point along the bottom wall of the tray near the hinge end of the tray and by hinging 20 a stiff link to this lever and to the bottom wall of the tray so that when swinging the cover from closed position, the lever serves to pry up through the rigid link the tray to incline it with reference to the bottom of the body member.

25 With reference to the drawings, 10 designates the body member and 11 the cover member. The body member has a bottom wall 12 and upstanding walls therefrom, there being a front wall 13, side walls 14—14 and a back wall 15.

The cover member has a top wall 16 and downwardly extending walls therefrom, there being a front wall 17, side walls 18—18 and a back wall 19.

30 The back walls 15 and 19 are hinged together by a metal hinge having plates 20 and 21 with a pintle pin 22 joining them. An arcuate spring serves to draw the hinge plates toward each other, as shown in Figure 3, and serves to swing the cover away from the body after it has opened through a short arc. Hooks on the spring may engage the hinge and limit the opening movement of the hinged members. Thus, the hinge serves to hold the cover in open position as well as in closed position.

A tray designated generally 30 conforms generally to the shape of the body member of the box and has a bottom wall 31 and upstanding walls therefrom including a front wall 32, side walls 33—33 and a back wall 34. This tray is loosely mounted in the body member of the box at its 40 end nearest the hinge connection between the body and cover members.

The tray 30 may rest loosely within the body member of the box while a lining 35 may be secured along the under surface of the cover or top wall of the cover which may have a sheet

3

of some textile material 36 over it for enhancing its appearance. This lining 35 has a lever portion 37 at right angles to the top wall of the box of 31 a length to extend well into the body member to a point adjacent the bottom wall 12 of this body member. This lever is relatively stiff and maintains its angular relation to the top wall 16. A rigid link 38 is hinged as at 39 to the lower end of this lever 37 and is also hinged as at 40 to a point beneath the tray 30 and is secured to the tray by a portion 41 extending along the bottom of the tray and pinned thereto as at 42.

Assuming the parts to be in the position shown in Figure 3, if the cover member 11 is swung about its hinge 22 to the position shown in Figures 1 and 2, then the lever 37 through its stiff link 38 will swing the tray about the upper forward corner, which is at the upper edge of the front wall 32 of the tray, as a fulcrum so as to incline the tray to a position such as shown in Figures 1 and 2 with reference to the bottom wall 12 while the lower edge of wall 32 slides along the bottom 12. A deck or pad 45 may be provided within the tray to which the merchandise may be secured and supported thereby. This pad serves to enhance the appearance of the merchandise in some cases and may be formed of textile or similar decorative material.

I claim:

A display box comprising a body member having a bottom and upstanding back, side, and front walls, a cover member having a top and back, side, and front walls hinged to the body member along the back edge thereof to swing relative thereto through 90 degrees, a tray having a bottom and

upstanding front and side walls within the upstanding walls of the body member and with the upper edge of the front upstanding wall of the tray engaging the front upstanding wall of the body member and free to have its end nearest the hinge connection movable upwardly to incline the tray relative to the bottom, a lever rigidly secured to the cover member and downwardly extending, when the cover member is in closed position, toward the bottom into the body member and a rigid link hinged to the lever and hinged to the bottom of the tray at a point near the rear end thereof, said link when the cover is in closed position extending upwardly at an acute angle from the lever and supporting the end of the tray in elevated position so that when the cover member is closed, the tray will be in the body member but when the cover member is swung to open position, the lever through the link connection will tend to push the tray against said front wall of the body member and pry the end of the tray nearest the hinge to swing the tray about the upper edge of the front wall as a pivot and incline the tray with reference to the bottom.
